UNITED STATES PATENT OFFICE.

JOHN J. MEYER, OF NEW YORK, N. Y.

INSERTABLE JOINT.

Application filed October 16, 1924. Serial No. 744,017.

To all whom it may concern:

Be it known that I, JOHN J. MEYER, a citizen of the United States, and a resident of the city of New York, borough of Manhattan, in the county and State of New York, have invented a new and Improved Insertable Joint, of which the following is a full, clear, and exact description.

This invention relates to insertable joints 10 for soil pipes and has for an object to provide an improved construction wherein vertically sliding supports are provided to connect the lower part of the pipe line with the superimposed part.

Another object of the invention is to provide 15 an improved insertable joint which includes a sliding support with means for locking the support at different heights.

A still further object of the invention, 20 more specifically, is to provide an improved construction wherein a sliding support is presented formed either integral with a false bottom or independent thereof.

An additional object is to provide an improved 25 construction in which the part is a division of my prior application for patent, Serial No. 709,254.

In the accompanying drawing—

Figure 1 is an elevation of part of a soil 30 pipe line and part of the building through which it extends, said soil pipe line being broken away and shown in section at certain parts for better illustrating the invention.

Figure 2 is an enlarged vertical sectional 35 view through the upper part of the inserted pipe section shown in Figure 1 and the lower part of the superimposed pipe section.

Figure 3 is a perspective view of the 40 sleeve or sliding support shown in Figures 1 and 2.

Figure 4 is a view similar to Figure 2 but showing a slightly modified construction.

Figure 5 is a sectional view through Figure 4, approximately on line 5—5.

Figure 6 is a view similar to Figure 2 but showing a second modified form of the invention.

Figure 7 is a view similar to Figure 6 but showing a modified form of the invention 50 in which the loosely insertable members are used to act as supporting locks.

Figure 8 is a top plan view of one of the inserted supporting and locking members shown in Figure 7.

Figure 9 is a view similar to Figure 6 but

showing an additional form of the invention.

Figure 10 is a view similar to Figure 9 but showing a modified construction.

Referring to the accompanying drawing 60 by numerals, 1 and 2 indicate floors through which the pipe line 3 extends, said line being the usual soil pipe line found in houses and formed of a number of sections of pipe each 65 having a body and a bell or hub at one end for receiving the next superimposed pipe section.

Where the soil pipe line has been placed in a house and it is later desired to add a toilet 70 or other fixture, it is necessary to break away the plaster and another material covering the line and also to break one or more of the sections of the line in order to place in position the section 4 which may be a 75 Y, T or other structure acting as a branch line for the added fixture. In order to prevent the removal of all of the sections of pipe above the section 4, a wire or other means is used to temporarily support the 80 superimposed pipe sections so that the section 4 may be readily fitted into the hub of the inserted section 5. In order that this 85 may be done, the hub end of the section 5 is of special construction as particularly shown in Figures 1 to 3 inclusive. From these figures it will be noted that the hub 6 is removably connected with the enlargement 7 of section 5 by suitable threads. The threaded section 8 may extend outwardly as 90 illustrated in Figure 2 or may be cut in the upper end of the enlargement 7 as preferred. It will be noted that the upper end of the enlargement 7 forms the bottom to the hub but it is necessary to support the pipe 4 above this bottom. In order to do this a 95

ring 9 forming the false bottom with a sliding support or sleeve 10 is provided to support the section 4 and at the same time present a false bottom for the hub as illustrated in Figure 4.

It will be noted that the ring 9 is loosely positioned and may be inserted after the sections 4 and 5 have been aligned but before the hub 6 is screwed into position. Sometimes it is desirable to support the pipe section 4 at a higher level than shown in Figure 2 and when this is the case the sleeve 10 is elevated the desired extent and the reduced end of the screw 11 is positioned in the appropriate notch 12 formed in the support 105 110

or sleeve 10. It will be noted that the bottom of the enlargement 7 is formed with an upwardly curved portion 13 and the support 10 is formed with a corresponding curve 14 which snugly fit together when positioned as shown in Figure 2. If the sleeve or support 10 is rotated for part of a revolution and the screw 11 inserted into the vertical slot 15, the sleeve 10 will be held 5 in a slightly elevated position so that the ring 9 will be raised above the upper end of the enlargement 7. If desired, the sleeve or support 10 may be manually adjusted until the screw 11 fits into any of the laterally extending notches 16 of slot 15 and in that way lock the support or sleeve 10 in different vertical planes. It will, of course, be understood that as the support 10 is raised or lowered ring 9 will be correspondingly raised and lowered and thus adjusted 10 so as to take care of the space between the lower end of section 4 and the upper end of the enlargement 7 of section 5. After the parts have been adjusted to the desired 15 elevation, suitable oakum or other fibrous packing 17 may be inserted and then the usual lead packing 18. This presents a water and gas tight connection.

In Figures 4 and 5, a modified construction 20 is shown wherein the vertical sliding support 19 is provided with a plurality of notches 20 in one part of its periphery, said notches being capable of mating with the bore or passage-way 21 in the enlargement 7' whereby the rod or supporting pin 22 may be inserted and partly extend into the bore or passage-way 21 and partly into the notch or groove 20. In this way, the rod 22 may 25 act to lock the support 19 in different vertical planes so as to support the ring or false bottom 9' in different vertical planes. The rod or pin 22 is preferably provided with an enlarged threaded section 23 screwing into a threaded bore in the enlargement 30 7' whereby the same cannot be accidentally removed.

In Figure 6, a further form of the invention 35 is shown wherein the support 10' is formed with a flange 24 at the upper end which is integral with the body of the support 10 instead of separately as shown in Figure 2. The support 10' may be made otherwise similar to that shown in Figure 2 or may have a number of apertures 25 into 40 which a supporting pin 26 is adapted to be forced, said pin being capable of being positioned on top of the enlargement 7" of section 5 or may be positioned in the aperture 27. As shown in the drawing, the screw 45 6 is arranged on top of the enlargement 7" while the filling plug 28 closes the threaded aperture 27.

In Figures 7 and 8, a further form of 50 the invention is shown wherein divided rings 29 and 30 are used for supporting the

supporting member or sleeve 10'. In Figure 7 two sets of rings have been provided but it is evident that more or less could be used according to different conditions.

In Figure 9, another form of the invention 55 is shown wherein the flange 24 of the supporting sleeve 10' is provided with one or more screws 31 extending substantially parallel to section 5. These screws are arranged in the flange 24 and bear against the upper end of the enlargement 7 whereby they may be adjusted to cause a proper support for the pipe section 4.

In Figure 10, a slightly different structure 60 from that shown in Figure 9 is illustrated. In this form of the invention, the various screws 32 are threaded into the enlargement 7 and in order to secure a vertical adjustment of the support 10', these screws may be rotated in the desired direction for 65 causing the support to be raised and lowered.

It will be seen that the sleeve or its rim 70 may be supported directly on the horizontal top wall adjacent the larger bore of said pipe section by pins or set screws penetrating into the sleeve and resting on the top of the wall or partly sunken into the top wall. Also, adjustable set screws may be 75 threaded into the rim and rest on the top wall of the pipe section or screws may be threaded into the top of the pipe section and extended to raise the sleeve and rim to different heights or shims of straight or half circular forms may be slipped under 80 the rim to extend and support the same.

It will be further seen that the sliding sleeve 10 may be partly turned on the cam 85 13 to elevate the sleeve to different heights and that the ring 9 may be rigidly secured to the sleeve 10 or made integral therewith as shown in Figure 6, or the ring may be omitted and the upper end of the sleeve 10 may abut the superimposed pipe. The inclined notches 16 in the sleeve 10 may be 90 slanted or cam-shaped to give vertical adjustment. The pipe 4 may telescope partly into the bore of the enlargement 7 if desired to facilitate insertion and the sleeve may be 95 made shorter, or the sleeve may be omitted, removed and replaced.

What I claim is:

1. An insertable joint for soil pipes, comprising a pipe section having an enlarged end, a tubular support arranged in said enlarged end formed with an annular flange at the upper end, a hub removably connected with said enlarged end surrounding said flange, and a removable screw acting on said enlarged end and said tubular support for 100 supporting the tubular support, means for holding said tubular support and flange so that a portion of said tubular support and flange will project above the horizontal end of the larger bore at different points 105 120 125 130

above said horizontal end to form a support for a superimposed pipe.

2. An insertable joint for soil pipes, comprising a pipe section having an enlargement at one end, a hub connected to said enlargement, a sleeve slidably mounted in said enlargement, said sleeve having a plurality of openings therein, and a supporting member carried by said enlargement 10 adapted to engage the sleeve in one of the openings so as to support the sleeve in the enlargement, said sleeve acting as a support for a superimposed pipe in said hub.

3. An insertable joint for soil pipes, comprising a pipe section formed with a bore at one end of larger diameter than the bore of said pipe section, a vertically sliding sleeve mounted in said larger bore acting as a reserve means for supporting a superimposed pipe above the hub bottom when necessary, said larger bore acting as a storage chamber for said sleeve and set screw adjusting means on the wall of said pipe section adjacent the larger bore end and engaging said sleeve, said set screw adjusting means acting as a support for said sleeve, and a removable lead filler hub attached to the wall forming said larger bore.

4. An insertable joint for soil pipes and the like, comprising a pipe section formed with a tubular second bore at one end of larger diameter than the bore of said pipe section, a hub of the caulked lead filler type removably attached to the exterior of the walls forming the second bore and presenting a third bore of larger diameter than the second bore, a supporting sleeve slidably mounted in the second bore and adapted to extend partly into the third bore when supporting a superimposed pipe, said sleeve being formed with an outwardly extending flange adjacent the top and integral with the sleeve, a removable support fitted laterally on top of the wall forming the second bore 40 for supporting said sleeve at different heights in the second and third bores, said removable support bearing on only a part of the surface of the extreme top of the wall forming the second bore.

5. An insertable joint for soil pipes and the like, comprising a pipe section formed with a tubular second bore at one end of larger diameter than the bore of the pipe section, a hub of the caulked lead filler type removably attached to the exterior of the walls forming the second bore, said hub presenting a third bore, a supporting sleeve in the second bore adapted to slide vertically 55 and to extend partly into the third bore when supporting a superimposed pipe, and a pin engaging said sleeve and the wall forming the second bore for supporting said sleeve.

6. An insertable joint for soil pipes and the like, comprising a pipe section formed

with a smooth tubular second bore at one end of larger diameter than the bore of the pipe section, a hub of the caulked lead filler type removably attached to the exterior of the wall forming the second bore, said hub presenting a third bore, a supporting sleeve in the second bore adapted to slide in a straight up and down direction and to extend partly into the third bore when supporting a superimposed pipe at different heights, and means for holding said sleeve in the second and third bores when said sleeve is elevated by a straight upward sliding movement.

7. An insertable joint for soil pipes and the like, comprising a pipe section formed with a second bore at one end of larger diameter than the bore of the pipe section, said second bore being free of obstructions, a hub of the caulked lead filler type removably attached to the exterior of the wall 70 forming the second bore, said hub presenting a third bore, a supporting sleeve snugly fitting into the second bore adapted to slide so that the sleeve when in supporting position will extend into the third bore for supporting a superimposed pipe in said bore, and a screw member engaging the side wall of said sleeve and the wall forming said second bore for supporting said sleeve.

8. An insertable joint for soil pipes and the like, comprising a pipe section formed with a second tubular bore at one end of larger diameter than the bore of the pipe section, a hub of the caulked lead filler type removably attached to the exterior of the wall forming the second bore, said hub presenting a third bore, a supporting sleeve in the second bore adapted to slide vertically and to extend partly into the third bore when supporting a superimposed pipe, said sleeve being formed with an outwardly extending flange integral with the top of the sleeve, and set screw means on the wall forming the second bore acting as a support for said sleeve and its flange.

9. An insertable joint for soil pipes and the like, comprising a pipe section formed with a smooth tubular second bore at one end of larger diameter than the bore of the pipe section, a hub of the caulked lead filler type removably attached to the exterior of the wall forming the second bore, said hub presenting a third bore, a smooth round supporting sleeve in the second bore adapted to slide straight up and down and to extend partly into the third bore for supporting a superimposed pipe at a variable height.

10. An insertable joint for soil pipes and the like, comprising a pipe section formed with a tubular second bore at one end of larger diameter than the bore of the pipe section, a hub of the caulked lead filler type removably attached to the exterior of the wall forming the second bore, said hub

- presenting a third bore, a supporting sleeve in the second bore adapted to slide vertically in a straight line and to extend partly into the third bore when supporting a superimposed pipe, said sleeve being formed with an outwardly extending flange integral with the top of the sleeve, and means between said flange and lower end of said sleeve acting to support said flange against the bottom of said superimposed pipe, said means resting on the wall forming said second bore, said second bore and exterior of said sleeve being round and smooth.
11. An insertable joint for soil pipe lines and the like, comprising a pipe section formed with a second bore at one end of larger diameter than the bore of said pipe section to allow a superimposed pipe to telescope into said second bore when said pipe section is inserted in said line, a removable filler joint hub attached to the exterior of said pipe section adjacent said second bore end, said hub forming a third bore in said insertable joint, a sliding supporting sleeve interposed between the sec-
- ond and third bore and extending into the third bore for supporting said superimposed pipe above the second bore, said sleeve having a bore approximately the same as the superimposed pipe and depending on the horizontal wall on top of the second bore for support.
12. An insertable joint for soil pipes having three bores of unequal diameter, the central bore being adapted to allow a superimposed pipe line to telescope temporarily therein when said joint is being inserted, a vertical supporting sleeve positioned between the superimposed pipe and the central bore for supporting said superimposed pipe in permanent position, said third bore being formed by a removable hub of the lead caulk filler type, said vertical supporting sleeve being supported on the horizontal top of the wall forming the central bore, said sleeve being capable of being withdrawn by a direct upward movement.

JOHN J. MEYER.
